UNITED STATES PATENT OFFICE.

WILLIAM E. HANN, OF CHICAGO, ILLINOIS, ASSIGNEE TO PULLMAN COUCH COMPANY,
OF CHICAGO, ILLINOIS, A CORPORATION OF ILLINOIS.

CONVERTIBLE FURNITURE.

1,216,443.

Specification of Letters Patent. Patented Feb. 20, 1917.

Application filed July 22, 1915. Serial No. 41,251.

To all whom it may concern:

Be it known that I, WILLIAM E. HANN, a citizen of the United States of America, and a resident of Chicago, county of Cook, and a resident of Illinois, have invented certain new and useful Improvements in Convertible Furniture, of which the following is a specification.

This invention relates to that type of sofa beds, bed davenport, and the like, in which the bed bottom when folded is disposed behind the back and seat and is pulled forward in converting the device into a bed.

The main objects of this invention are to provide a convertible bed device of the kind adapted for embodiment in either sofa or davenport form, and which may be arranged for mounting in an aperture in the wall of a room so as to constitute a combination wall-bed and sofa or davenport; to provide a neat and compact piece of furniture of small size both in depth and height, and which gives no indication that it is convertible into a bed; to provide such a piece of furniture with a deep seat having long upholstering springs, thereby providing a luxurious yielding seat; to provide such an arrangement of seat and sofa sections where in there is no waste space, it being all occupied by the seat and bed sections when folded; to provide such a device having few parts and which can be manufactured at a comparatively low cost; to provide such a device which may be easily operated by a woman or child and requiring but few motions in converting from sofa to bed form; to provide improved means for spacing the bed bottom away from the seat when extended to utilize the full action of the spring-bed bottom; to provide improved means for breaking the joints of the bed sections when the device is being folded back to its sofa form; to provide improved knock-down means permitting the sofa seat to be readily demountable; to provide improved automatic means for locking the outer bed sections in folded relation; to provide improved means for supporting the inner connecting section in bed position; and to provide an improved mounting for the sofa back, whereby it will be spaced away from the spring bed bottom when in its extended form, and will fit snugly against said bed bottom when in its sofa form.

Illustrative embodiments of this invention

are shown in the accompanying drawings, in which—

Figure 1 is a side view of a sofa bed with the near end of the sofa frame removed, and with the bed sections partly extended, the 60 relative positions of the parts when closed in sofa form being shown in dotted outline.

Fig. 2 is a section on the line A—A of Fig. 1.

Fig. 3 is a section on the line B—B of 65 Fig. 1.

Fig. 4 is a side view of a bed davenport with the near end of the frame removed and with the sections extended in bed form. Closed position of this embodiment is shown 70 in dotted outline.

Fig. 5 is a section on the line C—C of Fig. 4.

Fig. 6 is a section on the line D—D of Fig. 4.

Fig. 7 is a side view of an embodiment of the invention in which the sofa bed is built into an aperture in the wall of a room in such manner as to present the appearance of an ordinary sofa set close against the wall. 80

Fig. 8 is a section on the line E—E of Fig. 7.

Fig. 9 is a section on the line F—F of Fig. 7.

Fig. 10 is a fragmentary detail showing 85 the embodiment of Fig. 7 mounted in a sofa frame.

Fig. 11 is a side elevation of the bed sections of the sofa form when in their fully extended position. 90

Fig. 12 is an enlarged detail of the main and foot sections in folded relation with the locking members securing them together.

Fig. 13 is a side elevation of the same with the leg partly unfolded, with the locking 95 members in their released position.

Fig. 14 is a side elevation of the foot and outer connecting sections of the sofa wall-bed form showing the relative positions of the back and supporting legs when in bed 100 form.

Fig. 15 is an enlarged fragmentary side view of the locking device shown in Fig. 7.

Fig. 16 is a plan on the line G—G of Fig. 15. 105

Fig. 17 is a front elevation of one of the mounting plates which are secured to the inner sides of the upright ends of the sofa frame.

In the construction shown in Fig. 1, a 110

sofa bed is shown in which the bed bottom is extensible longitudinally across the frame of the sofa.

The sofa frame comprises upright ends 1 and connecting members 2. The ends 1 each have a mounting plate 3 secured by suitable means, as screws, to the inner sides thereof. These mounting plates, as best shown in Figs. 2 and 17, are provided with a U-shaped flanged recess 4 having an open mouth 5 of substantially the same size as the recess. A stud 6 is also provided on the plate 3 and is located above and slightly forward of the recess 4.

15 A deep framed sofa seat 7, equipped with long upholstering springs 8, is disposed between the ends 1 and is provided with plates 9 mounted on the ends thereof and so located as to be substantially opposite the plates 3 on the ends 1. Supporting means for the seat is provided, and comprises a short, heavy stud 10, preferably formed integrally with the plate 9, having a head 11 of substantially the same size as the recess 4 formed on the end thereof and shaped so as to be readily inserted in and removed from said recess through the mouth 5. Further support for the seat when in its normal sofa position is provided by one 25 30 of the connecting members 2.

Mounting of the seat in this manner permits of its pivotal rotation in a forward direction substantially 90 degrees until the front of the seat rests upon the floor, as shown in full lines in Fig. 1, thereby limiting the forward rotation of the seat and bringing the seat into position so as to bear upon the floor and assist in the supporting of the bed sections when in their 35 40 45 bed position. The sofa seat is so constructed that the upholstering on the top thereof extends to and fits snugly against the upright ends 1, as shown in Fig. 9, and the mounting plates and other mechanism are thereby entirely obscured from the most minute observer when the device is in its sofa form.

50 The bed bottom comprises a main section 12, a head section 13, a large connecting section 14 therefor, a foot section 15, and a small connecting section 16. A pair of supporting arms 17 are mounted one on each side of the main section 12 and extend forwardly between the ends 1 and the sofa seat, 55 the ends of the arms being provided with apertures to receive the studs 6 of the mounting plates 3. Each of the arms 17 at the end nearest the bed section, is embraced on either side by studs 18 mounted 60 on the frame of the sofa seat 7.

The head section is provided at its outer end with a bearing preferably in the form of a roller 19. A bearing surface for said roller in the form of an angle iron 20 is 65 secured in a vertical position to the sofa

frame at the rearward extremity thereof. Supporting means for the head section when in bed form, and means for breaking the joint 21 when the sections are to be folded, are provided and comprise a pair of members 22 and 23. Member 22 is preferably a piece of angle iron rigidly attached to the end 1 with the outstanding flange thereof on the upper convexly curved side, and the member 23 is a similar angle iron with the outstanding flange on the concavely curved upper and front side and is pivotally attached at its upper end 24 to the sofa frame end 1, the lower end 25 being shaped to normally rest upon the flange of the member 22.

70 75 80 85 The connecting section 14 is provided with a spacing bar 26 of the usual form and with a link 27 pivotally attached thereto at 28. The other end of the link 27 is pivotally attached to a depending lug 29 on the sofa seat frame at the point 30. When the device is in bed form this link is caused to assume a nearly vertical position by the shifting to the left, in Fig. 1, of the bed 90 sections relatively to the seat when being spaced away therefrom.

95 100 105 A sofa back 31 is mounted on and carried by the foldable bed sections by means of a bracket 32 rigidly secured to the rear side of the back and provided with a slot 33 adapted to receive a stud 34 on the main section 12. When the device is in sofa form this slot extends downwardly and rearwardly from the sofa back at an angle of about 45 degrees. The weight of the back when in this position causes it to fit closely and snugly against the bed section, and when in bed form to be spaced away from said section as shown in full lines in Fig. 1, thereby permitting full action of the spring bed bottom. The other end of the back is supported by a cord or strap 35 when the device is in bed form.

110 115 120 The foot section 15 is secured in folded relation with the main section 12 by means of locking members 36 and 37 pivotally attached to the sections at 38 and 39 respectively. (See Figs. 12 and 13). The member 36 is in the form of a lever, and is provided at one end thereof with a slot 40 having a recess 41 in the upper end thereof forming a shoulder 42 and provided at its other end at 73 with a pivotally mounted curved link 43. The locking member 37 has sliding connection with the member 36 by means of a pair of headed studs 44 and 45 mounted at the upper end thereof and shaped to slide in the slot 40.

125 Supporting legs 46 for the outer bed sections are connected together by a brace 57 and are pivoted to the foot section at 47, and the curved link 43 is pivoted thereto at 48.

A bedding fastener clamp 49 of usual 130

form is mounted on the end of the foot section at 58, and a spring 50 attached to the foot section is connected therewith to supply the necessary tension for holding the bedding during the folding operation. The short connecting section 16 is provided with a spacing bar 51 of the usual form. When the device is in sofa form this spacing bar is in position to be engaged by a latch 52 mounted on the sofa frame on the under side of the top connecting member 2. A push button 53 is arranged to operate the latch when it is desired to release the sections. Spring 54 is employed to automatically close the latch when the sections are being folded.

10 A lifting spring 55 is attached to the lower connecting member 2 and to the under side of the sofa seat frame at 56 to assist in unfolding the device.

20 The operation for converting the device from a sofa to a bed is as follows:

The operator first presses the button 53, thereby raising the latch 52 and releasing the spacing bar 51, thus permitting the lifting spring 55 to rotate the seat and bed bottom forward somewhat on their respective pivots. The operator then grasps the upper part of the bed bottom, back or spacing bar 51 and pulls forwardly. The joint 21 between the head and large connecting section is limited to 90 degrees in closing, and when the main section is lifted upwardly it carries the head section therewith, the bearing 19 on the end of the head section resting and traveling upon the support 20 until the main section is half way open. Upon further rotation of the main section, the head and connecting sections begin to straighten and to assume a horizontal position until the bearing 19 comes in contact with and rides upon the outstanding flange of the supporting member 22. The bearing 19, passing over the flange of the member 22, contacts with and raises up the pivoted member 23 and after the bearing 19 has passed under the end of the member 23, said member again assumes its normal position by gravity. The guide studs 18 on the frame 50 of the sofa seat coat with and lift up on the arms 17 during this forward rotation, and also permit the arms to slide therebetween, whereby the main section 12 is spaced apart from the back of the seat when in open position, thus permitting free action of the spring bed bottom. During this spacing away movement, the bed sections are carried to the left in Fig. 1 relatively of the seat, causing the connecting link 27 to assume a nearly vertical position for supporting the section 14. The back 31 slides downwardly and forwardly away from the bed section 12, when in this position, a sufficient distance to permit action of the spring bed bottom. The operator then grasps the cross

bar 57 which connects the legs 46 and lifts upwardly thereon. This initial unfolding of the legs unlocks the members 36 and 37 as shown in Fig. 13, and a further lifting on the legs or on the foot section 15 unfolds 70 the foot and connecting section 16 to the position shown in Fig. 11. The link 43, connecting the leg 46 with the locking member 36, unfolds the leg and causes it to assume a vertical position during this unfolding movement. The bedding fastener 49 is then lifted upwardly and outwardly and when its actuating spring 50 passes the pivotal center 58 it will be held in unfolded position as shown in Fig. 11.

80 The operation for folding the bed is as follows: The operator folds in the bedding fastener and grasps the end of the foot section, lifts upwardly thereon, folding the same over upon the main section 12 to the 85 position shown in Fig. 13. The weight of the legs and connecting brace when folded over in this manner will by gravity automatically press downwardly and cause the link 43 to swing the slotted end of the member 36 to the right, in Fig. 12, thereby engaging the stud 45 behind the shoulder 42 as shown in said figure. The points of attachment of the leg 46 to section 15 at 47 and of the link 43 to the leg at 48 and to 95 the locking member 36 at 73, are so arranged that when the legs are in their fully closed position the line of tension will be moved upward past the pivot 47 and the leg and members 36 and 37 will be locked in this 100 position by their own tension.

98 The spacing bar 51 is then grasped by the operator, lifted upwardly, and shoved backwardly toward the sofa frame, thereby causing the bearing 19 to ride up the inclined surface of the member 23, breaking the joints of the connecting section 14 and permitting the sections to fold together. When the bearing 19 has reached the top 105 of the member 23, it passes over the end 110 of the same and drops backwardly against the support 20 down which it travels during the remainder of the folding movement. During this folding movement the lower end 115 of the back to which the strap 35 is connected will swing in against the main section 12, and when the section 12 assumes approximately a vertical position, the stud 34 will slide forwardly in the horizontal portion of the slot 33 in the bracket 32, permitting 120 the back to slide backwardly and downwardly against the section 12 and somewhat back of the upholstered top of the sofa seat 7. The spacing bar 51 engages the inclined face of the latch 52 raising the same against 125 the action of the spring 54 until it passes by the shoulder of the latch when the entire device is automatically locked in sofa form.

When the demountable members are to be assembled in the sofa frame, the bed sec- 130

tions are first placed in the sofa frame in their folded position with the arms 17 projecting forwardly as shown in Fig. 7, the ends of the arms 17 being attached to the mounting plates 3 by means of the stud 6. The sofa seat is then slid between the end members 1 from the front thereof toward the rear, the studs 18 passing on opposite sides of the arms 17 until the headed stud 10 passes through the mouth 5 and into the flanged recess 4. The lifting spring 55 is then attached to the frame of the sofa seat at 56, thereby holding the supporting studs of the sofa frame in the recess 4 of the mounting plate 3. The seat and bed sections are then rotated forwardly to the position shown in full lines in Fig. 1, at which time the link 27 may be attached to the depending lug 29 of the sofa seat frame. The heads 11 on the supporting studs 10 being engaged in this manner give additional rigidity to the ends 1 of the sofa frame and prevent said ends from being spread.

In the embodiment shown in Fig. 4, the foot, connecting section and leg locking members of Fig. 1 are omitted, thereby making a one-motion bed davenport. In all other respects the construction and operation are the same as the embodiment shown in Fig. 1.

In the embodiment shown in Fig. 7, a foldable sectional bed bottom, substantially like that shown in Fig. 1, is disposed in an aperture in a wall and is so constructed and arranged as to give the appearance of a sofa set close to the wall.

A latch 59 provided with a push button 60 is mounted in the wall 70, and is arranged to automatically lock the bed sections in folded relation in the wall aperture 72. In this embodiment the leg 46 is operated by a link 61 attached to the foot connecting section at 62, as best shown in Figs. 14 and 15. Locking means for the sections 12 and 15 are provided in the form of an arm 63 rigidly mounted on the leg 46 and provided at its lower end with a curved foot 64. A stud 65 is located on the main section 12 in position to guide the curved heel of the foot 64, thereby pushing the toe 66 under the end of a locking link 67 which is pivotally mounted on the connecting section 14 and slidably connected to the section 12 by a headed stud 68 which is shaped to travel in an inclined slot 69.

The operation of this embodiment is practically the same as that of the embodiment shown in Fig. 1, except that the foot section is partially locked when said section is folded over the main section, bringing the toe 66 of the foot 64 under the end of the locking arm 67, and is fully locked when the sections are folded to bring the head connecting section 14 at substantially right angles to the main section 12. This folding

carries the pivoted end of the locking arm upwardly and toward the foot, the other end of the arm passing over and securing said foot as shown in Fig. 1.

The embodiment of Fig. 10 shows how the construction of the embodiment shown in Fig. 7 can be mounted in a sofa frame of the form shown in Fig. 1.

Although several embodiments of this invention are herein shown and described, it will be understood that numerous details of the constructions shown may be altered or omitted without departing from the spirit of this invention as defined by the following claims.

I claim:

1. A device of the class described, comprising a frame including ends and connecting means therefor, a rotatable seat disposed between said ends and demountably attached thereto, a foldable sectional bed bottom disposed normally behind said seat and extensible forwardly above said seat in bed position, supporting means for said bed bottom mounted turnably on said frame, and means connecting said seat and said supporting means for rotating the same, said seat being shaped and positioned so as to coöperate with said supporting means through said connecting means for supporting said bed bottom when in its bed position.

2. In a device of the class described, a frame including ends and connecting means therefor, a seat disposed between said ends and pivotally mounted thereto, said seat having a deep frame and being provided with large upholstering springs, a foldable sectional bed bottom including a plurality of sections disposed normally behind said seat in substantially upright position, and supporting means for swinging said bed bottom forwardly from its position behind the seat, said seat and supporting means being turnable about fixed axes respectively for rotating said seat to an edgewise position.

3. In a device of the class described, a frame including ends and connecting means therefor, a seat disposed between said ends and pivotally mounted thereon for rotating forward on edge to its bed position, in combination with a foldable sectional bed bottom disposed normally behind said seat with its long sections in a substantially upright position, and means supporting said bed bottom for swinging the same together with said seat forwardly to bring said long sections in a substantially horizontal position above the upturned rear edge of said seat.

4. In a device of the class described, a frame including ends and connecting means therefor, a seat disposed between said ends and pivotally mounted thereon for rotating forward to its bed position, in combination with a foldable sectional bed bottom disposed normally behind said seat, supporting

120

125

130

means for said bed bottom having sliding operative connection with said seat for swinging said bed bottom forwardly when said seat is turned forward on its pivot, and 5 means adapted to urge the seat to swing forward.

5. In a device of the class described, a frame including ends and connecting means therefor, a seat disposed between and rotatably mounted on said ends, a foldable sectional bed bottom disposed normally behind said seat, supporting arms for said bed bottom pivoted to said ends at a point above the pivoted mounting of said seat, and connecting means between said arms and seat 10 for swinging said bed bottom forwardly when said seat is turned forward on its pivot.

6. In a device of the class described, a frame including ends and connecting means therefor, a seat disposed between and rotatably mounted on said ends, a foldable sectional bed bottom disposed normally behind said seat, supporting arms for said bed bottom pivoted to said ends, connecting means 15 coaxing between said arms and seat adapted to cause said bed bottom and said seat to swing forward and back coaxively, the pivoted points of said arms and said seat being so disposed relatively to each other that said bed bottom is spaced away from said seat when in its bed form, and is in close proximity to said seat when in its sofa form.

7. In a device of the class described, a frame including ends and connecting means therefor, a seat disposed between and rotatably mounted on said ends, a foldable sectional bed bottom disposed normally behind said seat, supporting means pivoted to said 20 ends for holding said bed bottom in close proximity to the seat when in sofa position, and for holding said bed bottom spaced away from said seat when in bed position, and connections between said supporting 25 means and seat for swinging said bed bottom forwardly when said seat is rotated forwardly on its pivots.

8. In a device of the class described, a frame including ends and connecting means therefor, a seat disposed between said ends and pivotally mounted thereon, a foldable sectional bed bottom disposed normally behind said seat and comprising a main section, a head section, and a connecting section, supporting arms for said main section 35 pivoted on said ends, and a link joining said connecting section with said seat.

9. In a device of the class described, a frame including ends and connecting means therefor, a seat disposed between said ends and rotatably mounted thereon, a foldable sectional bed bottom disposed normally behind said seat and comprising a main section, connecting sections on each end of said

main section, a foot section attached to one of said connecting sections, and a head section attached to the other of said connecting sections, and means for swinging said seat and bed bottom forward coaxively to their 70 bed position.

10. In a device of the class described, a main section, a foot section, and a connecting section, a leg pivoted to one of said sections, a lock comprising a pair of members pivoted to the main and foot sections respectively, said members having connections with each other and with said leg for locking said sections together when said leg is in its completely folded position, and for 80 releasing said sections when said leg is partially unfolded.

11. In a device of the class described, a main section, a foot section, and a connecting section, a leg pivoted to one of said sections, a lock comprising a pair of members pivoted to the main and foot sections respectively, one of said members being provided with a slot having a recess in the side thereof of forming a shoulder, and the other of said 90 members having a part thereof shaped to travel in said slot, and means connecting said locking members with said leg for causing the said part of one locking member to be engaged and secured by the shoulder of 95 the other locking member when said leg is in its completely folded position, and for unlocking said members when said leg is partially unfolded.

12. In a device of the class described, a frame including ends and connecting means therefor, a seat disposed between said ends and turnably mounted thereon, a foldable sectional bed bottom disposed normally behind said seat and comprising a main section, connecting sections on each end of said main section, a foot section attached to one of said connecting sections, a head section attached to the other of said connecting sections, means for swinging said seat and bed bottom forward coaxively to their bed position, and means for locking said foot and main sections together when folded substantially parallel with each other.

13. In a device of the class described, a frame including ends and connecting means therefor, a seat disposed between said ends and pivotally mounted thereon, a foldable sectional bed bottom disposed normally behind said seat and comprising a main section, a head section and a connecting section, a bearing on said head section, and coöperating supporting means for said bearing comprising a stationary member and a movable member, said movable member being pivoted 125 at its upper end and having its lower end shaped to rest on said stationary member.

14. A foldable sectional bed bottom comprising a pair of sections foldable together in spaced parallel relation, in combination 130

- with a lock including a pair of bars pivoted to said sections respectively near their adjacent edges, said bars being formed to overlap at all times and having coacting guide means including a pair of shoulders on said bars respectively, and means for turning said bars to throw said shoulders into locking engagement when the sections are folded.
- 10 15. A bed bottom lock comprising a pair of overlapping bars formed and arranged to reciprocate longitudinally, said bars at their outer ends being pivoted to the sections to be locked respectively; means operable manually for turning of said bars somewhat when the sections are folded, said bars having coacting means engageable by such turning.
- 15 20. A device of the class described, comprising a frame and a deep seat member having its lower front part turnably connected to the lower front part of said frame for turning forwardly, in combination with a foldable sectional bed bottom disposed normally in upright folded position behind said seat member, one of the sections having a pair of arms, one at each side, whereon said section is swingable forwardly to its bed position, each of said arms being turnably connected to said frame somewhat above and forward of the seat turning axis, means on said frame for supporting the inner part of the bed bottom turnably, and a pair of links, one on each side, each having its ends turnably connected to the rear upper part of said seat member and to an adjacent part of the bed bottom respectively
- 25 30 35
- for supporting the latter, said seat and arms being formed and arranged for co-turning to and from bed position.
17. An article of convertible furniture comprising a support including end members spaced apart, in combination with a sectional bed bottom mounted foldably between said end members, a seat mounted overturnably between said end members, and slidably coacting means operatively connecting said bed bottom and seat whereby the overturning and restoring movements of the latter are dependent upon the corresponding forward and rearward movements of the former respectively, said bed bottom and seat having relative movement.
18. An article of convertible furniture comprising a support including end members spaced apart, in combination with a sectional bed bottom mounted foldably between said end members, coacting means on said support and bed bottom respectively for supporting and guiding the latter, a seat mounted overturnably between said end members, coacting means on said support and seat for supporting the latter, and means operatively connecting said bed bottom and seat whereby the overturning and restoring movements of the latter are dependent upon the corresponding forward and rearward movements of the former respectively, said bed bottom and seat having relative movement.
- Signed at Chicago this 17th day of July
1915

WILLIAM E. HANN.
